UNITED STATES PATENT OFFICE.

GRANT L. HOUSTEAU, OF YOUNGSTOWN, OHIO.

WINDOW LOCK.

Application filed June 13, 1925. Serial No. 38,043.

To all whom it may concern:

Be it known that I, GRANT L. HOUSTEAU, a citizen of the United States, residing at Youngstown, in the county of Mahoning and State of Ohio, have invented certain new and useful Improvements in Window Locks; and I do declare the following to be a full, clear, and exact description of the invention, such as will enable others skilled in the art to which it appertains to make and use the same.

My invention aims to provide an exceptionally simple and inexpensive, yet an efficient and desirable device which is adapted for quick and easy application to a window and may be used for holding the upper and lower sashes in any desired relatively adjusted positions.

The device comprises in general, a guide member adapted to be mounted on the upper rail of the lower window sash, and a wedge slidably engaged with said guide member, further objects being to provide a wedge and a guide member of unique construction, and to make novel provision for holding the wedge in an inoperative position when its use is not desired.

With the foregoing in view, the invention resides in the novel subject matter hereinabove described and claimed, the description being supplemented by the accompanying drawing.

Figure 1 is a perspective view showing the application of the invention.

Figure 2 is a vertical sectional view illustrating the wedge in operative position in full lines and by dotted lines showing its inoperative position.

Figures 3 and 4 are perspective views of the wedge looking in different directions.

Figures 5 and 6 are perspective views of the guide member looking in different directions.

The drawing above briefly described may be considered as illustrating the preferred form of the invention and while the construction shown will be hereinafter rather specifically described, it is to be understood at the outset that within the scope of the invention as claimed, modifications may be made.

The numeral 1 designates in a general way, a wedge guiding member. This member comprises a substantially vertical plate 2 having a central neck 3 projecting up-

wardly from its upper edge, said neck being provided with oppositely projecting fingers 4. The end portions 5 of the upper edge of the plate 2, form shoulders at opposite sides of the neck 3 for a purpose to be hereinafter explained, and at the ends of these shoulders, lugs 6 are bent laterally from one side of the plate. The upper end of the neck 3 is preferably curved in the same direction in which these lugs extend, as shown, and the lower end of the plate 2 has been shown bent in this same direction to provide a horizontal ledge 8. Vertical wings 9 project in the opposite direction from the plate 2, at the vertical edges of the latter, the lower ends of these wings being bent laterally inward to provide attaching feet 10 which are adapted to be secured by screws or the like 11 to the upper rail 12 of a lower window sash.

The entire guide member 1 is preferably stamped from a single piece of suitable gauge sheet metal, as will be clear from the drawing.

At 13, I have shown a hollow wedge formed of sheet metal, one side wall of said wedge being produced by inwardly bending a pair of flanges 14 from two adjacent side walls, as shown, a space being left between the two flanges, forming a longitudinal slot 15. There is also an open space 16 between the upper ends of the flanges 14 and the upper end of the wedge. The flanges 14 slidably engage the shoulders 5, and the neck 3 passes through the slot 15, the fingers 4 then slidably engaging the inner sides of said flanges. In this connection, it may be explained that these fingers are passed through the opening 16, when assembling the device. In addition to the guiding influence exerted by the flanges 14, neck 3, fingers 4 and shoulders 5, it will be seen that the lugs 6 embrace the wedge 13 to further guide the same. The side of the wedge, opposite the flanges 14, is preferably provided with spurs 17 outwardly stamped therefrom to engage one of the side rails of an upper sash, when the wedge is in the operative position shown in Figs. 1 and 2. However, when the use of this wedge is not needed, it may be raised and its lower end 18 then engaged with the ledge 8 as shown in dotted lines in Fig. 2.

The wedge is held in either position, against accidental upward movement, by a coiled tension spring 19 whose lower end is connected to the neck 3 while its upper end is 110

suitably connected to the upper end of the wedge, the latter being preferably provided with a tongue 20 for this purpose.

Normally, it may be considered that the 5 wedge 13 occupies the dotted line position of Fig. 2, so as to permit free sliding of the sashes. When they have been relatively adjusted however, the wedge may be easily moved off of the ledge 8 so that the spring 10 19 snaps it downward into operative position, thus effectively locking both sashes.

On account of the advantages existing for the details shown, they are preferably followed, but as above stated, modifications 15 may be made within the scope of the invention as claimed.

I claim:

1. A sash fastener comprising a guide member adapted to be secured to the upper 20 rail of a lower sash, said guide member having a ledge, and a spring-locked wedge slidably engaged with said guide member, said wedge being adapted to be tilted and disposed on said ledge when not in use, 25 whereby it is held against downward movement.

2. A sash fastener comprising a guide member adapted to be secured to the upper

rail of a lower sash, said guide member having an upstanding neck and horizontal 30 shoulders at opposite sides thereof, said neck being provided with oppositely projecting fingers spaced from said shoulders, and a hollow wedge having a longitudinal slot in one side wall through which said neck 35 passes, the aforesaid shoulders engaging the outer side of said wall and said fingers engaging the inner side thereof.

3. A sash fastener comprising a substantially vertical sheet metal plate having wedge-guiding means at its upper end, the lower end of said plate being bent horizontally to provide a ledge at one side of the plate, vertical wings bent laterally from the plate and projecting from the other side thereof, said wings having horizontally bent lower ends forming attaching feet, a wedge 40 slidably engaged with said wedge guiding means and adapted to rest on said ledge when not in use, and spring means connecting said wedge and plate and exerting a downward stress on the former.

In testimony whereof I have hereunto affixed my signature.

GRANT L. HOUSTEAU.
